UNITED STATES PATENT OFFICE.

CHARLES P. SWEENEY AND HORATIO WRIGLEY, OF PHILADELPHIA,
PENNSYLVANIA.

DESIGN FOR A BASE FOR COIN-SCALES.

SPECIFICATION forming part of Design No. 28,669, dated May 17, 1898.

Application filed May 1, 1897. Serial No. 634,781. Term of patent 7 years.

To all whom it may concern:

Be it known that we, CHARLES P. SWEENEY and HORATIO WRIGLEY, citizens of the United States, residing in the city and county of Philadelphia, State of Pennsylvania, have invented and produced a new and original Design for the Base of a Coin-Scale, of which the following is a specification, reference being had to the accompanying drawings, forming part thereof.

The leading feature of our design for the base of a coin-scale is a base consisting of a block and an upwardly-pointing indicating-finger rising from the side thereof.

5 Figure 1 represents a perspective view of the base of a coin-scale embodying our de-

sign. Fig. 2 represents a vertical section on line x x , Fig. 1.

Referring to the drawings, A designates the base of a coin-scale, the same consisting of 20 the block B, the indicating-finger C, and the standard D. The indicating-finger rises from said base at the side thereof and projects above the upper edge thereof.

What we claim is—

25 The design for the base of a coin-scale substantially as shown and described.

CHAS. P. SWEENEY.
HORATIO WRIGLEY.
